[57] CLAIM

The ornamental design of a portable animal carrier, as shown and described.

DESCRIPTION

FIG. 1 is a right side elevational view of a portable animal carrier showing my new design, the left side being a mirror image of the right side shown;

FIG. 2 is a top plan view thereof showing the closure in a partially open position;

FIG. 3 is a bottom plan view thereof;

FIG. 4 is a front elevational view thereof; and

FIG. 5 is a rear elevational view thereof.

FIG. 1

FIG. 4

FIG. 5
